UNITED STATES PATENT OFFICE

2,573,696

SAFETY FEED CONTROL DEVICE FOR
OIL BURNERS

Joseph Dominic, Botwood, Newfoundland

Application December 31, 1948, Serial No. 68,637

3 Claims. (Cl. 137—68)

1

This invention relates to oil burners, and more particularly to an oil control device for regulating the flow of oil to a burner so as to maintain the level of oil in the burner at a safe value at all times.

A main object of the invention is to provide a novel and improved fuel feed control device for oil burners which prevents the oil level in the burner from rising to a dangerous point through inadvertent opening of the manual control valve of the burner, through accidental extinction of the burner flame, or for any other reason, whereby the burner is protected against the hazards arising from excessive oil in the burner.

A further object of the invention is to provide a novel and improved safety device to limit the quantity of oil admitted to an oil burner to a safe value at all times, said device being very simple in construction, easy to install and entirely automatic in operation.

Further objects and advantages of the invention will become apparent from the following description and claims, and from the accompanying drawings, wherein:

Figure 1 is a generally schematic view of the fuel supply system of an oil burner provided with a fuel feed control device constructed in accordance with the present invention, the carburetor and the feed control device being shown in longitudinal cross-section.

Figure 2 is a fragmentary cross-sectional view taken on line 2—2 of Figure 1.

Figure 3 is an enlarged cross-sectional detail view taken on line 3—3 of Figure 1.

Figure 4 is an enlarged cross-sectional detail view taken on line 4—4 of Figure 1.

Figure 5 is a fragmentary top plan view of the manual control element of the oil burner, as shown in Figure 2, but illustrating the control knob in the "on" position.

Referring to the drawings, 11 generally designates an oil burner having a fuel inlet sump 12, the burner being of the conventional gravity feed type wherein the fuel flows upwardly into the burner through said inlet portion 12. The fuel is supplied from an elevated storage tank 13 through a conventional float chamber 14. As shown in Figure 1, a conduit 15 connects the bottom of supply tank 13 to the inlet manifold 16 of the float chamber 14. The fuel is admitted into the chamber through the usual float-controlled needle valve 17, said valve being provided with a manually latched float-operated closing mechanism, indicated generally at 18 for closing the valve under certain conditions such as when sediment in the seat portion of valve 17 obstructs normal closing thereof. The structure of the chamber 14 is well known and is described in detail in U. S. Patent No. 2,129,937 to R. W. Johnson, issued September 13, 1938.

Chamber 14 is provided with an outlet valve 19 which is operated by a cam 20 acting against an arm 21 in a well known manner. Rotation of cam 20 is accomplished by a shaft 22 provided at

2

its top end with a knob 23. The float chamber valve 19 may be opened to a desired degree by adjusting knob 23, with reference to a scale marked adjacent the cam housing 24, as shown in Figures 2 and 5. The structure thus far described is conventional and forms no part of the present invention.

The operation of the float chamber 14 normally maintains a constant level of fuel in the burner while the valve 19 is open and the burner is in operation. However, if the burner is not in operation and valve 19 is opened, the level of fuel in the burner may rise more rapidly than the level of fuel in the chamber, and when the carburetor float valve closes, it may leave the burner with an excessive amount of fuel, particularly where sediment is present in valve 18 and the closing mechanism 18 fails to operate promptly or has not been properly latched.

20 The present invention aims to prevent the excessive accumulation of fuel in the burner from any cause. In accordance with the invention, a float valve-operated safety device, shown generally at 25 is interposed between the chamber 14 and the burner 11. Safety device 25 comprises a chamber 26 having an intake passage 27 formed in its bottom wall, said passage 27 being connected to the outlet of chamber 14 by a conduit 28. Connected to passage 27 inside the 25 chamber 26 is a vertical valve sleeve 29, apertured at its lower portion as shown at 30, and formed adjacent aperture 30 with a valve seat 31. Slidably positioned in valve sleeve 29 is a needle valve 32 provided with a washer 33 at its upper portion. A coiled spring 34 encircles the needle valve 32, bearing between washer 33 and sleeve 29. Washer 33 is located on a reduced stud portion 36 at the top end of valve 32. Encircling stud portion 36 is a second coiled spring 35 which 30 bears between washer 33 and a second washer 37 on stud portion 36. A nut 38 is threaded on said stud portion above washer 37 to provide adjustable spring pressure on washer 37. Pivoted on a transverse shaft 39 in chamber 26 is an arm 40 carrying a float 41 at one end and bearing on washer 37 at the other end. Float 41 is set to force needle valve 32 downwardly against seat 31 when the oil level in chamber 26 reaches the desired limiting safe level in the burner sump 12.

45 Designated at 42 is a vertical outlet valve sleeve secured in chamber 26 and connected to a conduit 43 leading to the burner inlet sump 12. Sleeve 42 is apertured at its lower portion, as shown at 44. Slidably positioned in sleeve 42 is a needle valve 45 provided with a top abutment 46. A coiled spring 47 encircles the upper portion of needle valve 45 and bears between abutment 46 and the top of sleeve 42. Vertically aligned with needle valve 45 and slidably passing through the 50 top wall of chamber 26 is a rod 48 having a bottom abutment 49. A coiled spring 50 encircles rod 48 and bears between abutment 49 and the top wall of chamber 26. Spring 50 exerts sufficient force to normally maintain needle valve 45

in seated position against the bottom seat portion, shown at 51, of valve sleeve 42.

Pivoted to an upstanding bracket 52 secured to the top wall of chamber 26, for rotation in a horizontal plane, is an arm 53. Arm 53 passes through a horizontally slotted guide bracket 54 carried by chamber 26 and is formed at its left end, as viewed in Figures 1 and 2, with divergent fingers 55, 55 extending on opposite sides of a vertical vane 56 carried by the manual control shaft 22. Designated at 57 is a cam member pivoted at 58 to an upstanding bracket 59 carried by the top wall of chamber 26 adjacent the upper end of rod 48. Cam member 57 is rotatable in a transverse vertical plane. The upper portion of said cam member is formed with spaced upstanding lugs 60, 60 defining a notch between which the right end of arm 53 is received, as viewed in Figures 1 and 2. A U-shaped link member 61 connects the top end of rod 48 to the upper portion of cam member 57, as shown in Figure 4.

Cam member 57 is formed with inclined depending lugs 62 and 63 which cooperate with the top wall of chamber 26 to limit rotation of the cam member in counterclockwise and clockwise directions respectively, as viewed in Figure 4. When the cam member is rotated clockwise, lug 63 engages said top wall shortly after the top arm of link 61 passes its dead center position. Rod 48 is therefore held in a raised position and the cam is held in this rotated position by the force of spring 50. When cam 57 is rotated counterclockwise from this latter position, spring 50 returns the cam to a position wherein lug 62 abuts the chamber top wall, as shown in Figure 4.

The counterclockwise rotation of cam member 57 allows rod 48 to move downwardly under the force exerted thereon by spring 50 to thereby move the needle valve 45 into seating position.

When knob 23 is rotated clockwise from the position shown in Figure 2, vane 56 engages the adjacent finger 55 of arm 53 and rotates said arm counterclockwise around its pivot bracket 52. This rotates cam 57 from the position shown in Figure 4 clockwise to a position wherein lug 63 abuts the top wall of chamber 26, the top arm of link 61 being meanwhile moved beyond dead center position, whereby the cam is held in this rotated position, as above described. Rod 48 is thus held in raised position, allowing needle valve 45 to be opened by spring 47 and allowing oil to flow from chamber 26 through conduit 43 to burner sump 12. Figure 5 illustrates the relative positions of vane 56 and arm 53 at this time. To close needle valve 45, knob 23 must be rotated counterclockwise from the position of Figure 5 to the position of Figure 2. This swings arm 53 clockwise around its pivot lug 52 and returns cam 57 to the position of Figure 4.

It is thus seen that needle valve 45 is raised only when the knob 23 is turned from its "off" position to its "on" position, and will remain open until knob 23 is returned to "off" position in the manner above described. During the time the needle valve 45 is open the float-operated needle valve 32 protects the burner from receiving too large a quantity of fuel from the chamber 14.

While a specific embodiment of a safety fuel feed control device for oil burners has been disclosed in the foregoing description it will be understood that various modifications within the spirit of the invention may occur to those skilled in the art. Therefore, it is intended that no limitations be placed on the invention except as defined by the scope of the appended claims.

What is claimed is:

1. In a fuel feed system for oil burners, a float chamber having a manually controlled outlet valve, an outlet conduit connected to said outlet valve, and a feed control device connected to said outlet conduit, said feed control device comprising a chamber having a float-controlled intake valve and an outlet valve mechanically coupled to the outlet valve of the first mentioned float chamber.

2. In an oil burner fuel feed system, a float chamber, said chamber having a manually controlled outlet valve, conduit means extending from said outlet valve, said conduit means including a second chamber having a liquid level-responsive intake valve and a normally closed outlet valve, a rotary notched cam member mounted on said second chamber for rotation in a vertical plane, link means connecting said cam member to said normally closed outlet valve, an arm pivoted to said second chamber for rotation in a horizontal plane normal to the plane of the cam member and engaging in the notch of said cam member at one end portion thereof, and cooperating means on said manually controlled outlet valve and the other end portion of said arm formed and arranged to rotate said arm responsive to actuation of said manually controlled valve.

3. In an oil burner fuel feed system, a float chamber, outlet valve means in said chamber, a rotary shaft provided in said chamber, means on said rotary shaft for actuating said outlet valve means, conduit means extending from the outlet valve means of the chamber, said conduit means including a second chamber having a float-controlled inlet valve and an outlet valve comprising an apertured sleeve member projecting vertically from the bottom wall of said second chamber, a valve rod slidably fitting said sleeve member, and spring means biasing said valve rod downwardly in the sleeve member, the top end of said valve rod projecting slidably through the top wall of said second chamber, a cam having a notched top portion and depending side lugs, means rotatably mounting said cam on the top wall of said second chamber for rotation in a vertical plane, said side lugs being respectively engageable with said top wall responsive to rotation of said cam, a link member connecting said cam to the top end of said valve rod, the valve rod being elevated responsive to rotation of said cam from one of its limiting positions to the other, and the connection of the link member to the cam being positioned beyond its upper dead center position when the cam reaches said other limiting position, whereby the spring means hold the cam in said other limiting position, an arm pivoted to the top wall of the second chamber, one end of said arm engaging in the notch of the cam, a pair of spaced fingers on the other end of said arm, and a projection on said rotary shaft engaging between said spaced fingers.
